NECKTIE HOLDER

Byron T. Bjork, Long Island City, N. Y.

Application April 7, 1936, Serial No. 73,178

3 Claims. (Cl. 2—156)

This invention relates to necktie holders, and more particularly to holders of the removable type designed to hold the necktie in place during the tying operation and to aid in that operation. 5 The principal object of the invention is to provide a simple and easily removable necktie holder and guide which will operate with equal facility on separate collars and on collars attached to shirts.

10 The preferred manner of construction and use of the invention will now be described with reference to the accompanying drawing, in which—

Fig. 1 is a transverse sectional view taken 15 through a collar and tie with the device fitted in place in the operative relation;

Fig. 2 is a rear elevation of the device detached from the collar; and

Fig. 3 is a rear elevation of the device in use 20 on a collar.

The device of the invention is made of sheet metal or other suitable material of resilient nature. In using the device on a separate collar, the necktie 10 is first placed in the groove between the part 7 and side pieces 4. The device and tie are then inserted, at a point adjacent the collar button hole, between the front 9 and the back 11 of the collar until the upper edges of side pieces 4 meet the inner top of the collar as shown 25 in Fig. 1. The lower edge of the back of the collar rests within the groove formed by hook 8. For best results the distance between the bend in hook 8 and the top of side pieces 4 should exceed 30 the height of the collar in order to avoid bending the latter. Part 6, which is made of suitable elastic material, is then stretched so that hook 5 may engage the upper edge of the collar. The collar is then attached to the shirt; the tie is adjusted and tied; and the device is removed by 35 disengaging hook 5, when the whole device can be withdrawn from the collar.

In using on a shirt with collar attached, the device with the necktie should be inserted in the

folds of the collar before the shirt is put on, and it should be removed as described above when the necktie is adjusted and tied.

The advantages of the device are in large measure apparent from the above description. It 5 greatly facilitates the adjusting and tying of the necktie by holding open the space between the folds of the collar while at the same time preventing the tie from sliding down below its proper place. In the same way it also protects 10 the necktie from wearing by friction with both the collar and the collar button. Also it is simple in construction and can therefore be made at low cost, and is easy to use for its intended purpose. It is especially useful in 15 protecting starched collars on shirts with collars attached from cracking during the insertion of the tie.

What is claimed is:—

1. A removable necktie holder comprising a 20 flat member of resilient material, a part thereof being bent to form a groove for the necktie, said flat member extending upwardly from said groove and normally engaging the fold line of the collar, and means for securing the holder in position on the outside of the collar during the tying operation. 25

2. A removable necktie holder comprising a flat member of resilient material, a part thereof being bent to form a groove for the necktie, said 30 flat member extending upwardly from said groove and normally engaging the fold line of the collar, another part being bent to form a hook, and means for securing the holder in position on the outside of the collar during the tying operation. 35

3. A removable necktie holder comprising a flat member of resilient material, a part thereof being bent to form a groove for the necktie, another part being bent to form a hook, a second hook, adapted to engage the top edge of the 40 collar and elastic means connecting said two hooks.
